UNITED STATES PATENT OFFICE

1,995,345

RACE TRACK PLANT

William E. Golden, Chicago, Ill.

Application April 23, 1931, Serial No. 532,295

3 Claims. (Cl. 20—0.5)

My invention relates to race track plants, this application being filed as a continuation in part of my former application Serial No. 449,602, filed May 3, 1930.

5 It is one of the objects of my invention to provide a new and improved form of grand stand and associated buildings, by virtue of which the patrons may be enabled better to see the track and may be seated in better and more cheerful 10 surroundings in general. It is one of the objects of my invention to provide an improved construction by which a canopy may be provided over the seats and extending some little distance in front without in any way interfering with the ability 15 of the patrons to see the full length of the track. It is another object of my invention to provide a structure of this type comprising a canopy extending out in front of the track and continuing to the rear in a cantilever arrangement to a series 20 of anchors to which connection is made for counterbalancing the forwardly projecting portion of the canopy.

It is another object of my invention to provide 25 glass enclosure means, preferably carried by the canopy and its supporting means, covering the space immediately in rear of the grand stand, providing park and promenade space over and about the paddock and such other features as may 30 form a part of the plant as a whole, the glass or other enclosing means for the rear portion of the canopy or perhaps for both the rear portion and the front portion being preferably of a type adapted to permit the passage of the full beneficial 35 ray of the sun therethrough.

It is another object of my invention to provide 40 an improved arrangement of the buildings occupied by the judges and the timers and such other buildings or other structures as are desirable in front of the grand stand, such improved arrangement being designed to insure a minimum of interference by such buildings with the view of the 45 patrons in the grand stand and the club house. For attaining this object to best advantage, I have mounted such small buildings on elevators arranged for lowering the buildings into pits below the level of the ground on each occasion during the actual running of the race.

It is another object of my invention to improve 50 plants of this type in sundry details hereinafter pointed out. The preferred means by which I have accomplished my several objects are illustrated in the drawings and are hereinafter specifically described. That which I believe to be new and desire to cover by Letters Patent is set 55 forth in the claims.

In the drawings,—

Fig. 1 is a perspective view from one end, partly broken away, showing the grand stand and the promenade in rear of the stand;

Fig. 2 is a perspective view of the structure of Fig. 1 as seen from the rear; and

Fig. 3 is a vertical section view through the building occupied by the timers on the inside of the track in front of the grand stand, such building being mounted upon an elevator so as to be lowered into a pit as shown in solid lines, the building in its raised position being indicated by dotted lines.

Referring now to the several figures of the drawings, in which corresponding parts are indicated by the same reference characters, 10 indicates a track, having fences 11 and 12 at opposite sides thereof. 13 indicates a grand stand of any improved construction, having a promenade or park 14 in rear thereof, including the usual paddock 15. The grand stand and promenade are covered by a canopy, comprising a portion 16 covering the grand stand and extending outwardly in front substantially to the edge of the track, and a portion 17 extending rearwardly from the grand stand over the promenade to a counterbalancing arrangement by reason of which the canopy portion 16 is supported without the use of columns at its front edge. A building 18 for the timers is shown in front of the grand stand.

In the construction as shown in Fig. 1, a series of cantilever beams 19 are supported at intermediate points by columns 20 and 21 carried by foundations 22 and 23 respectively, the rear end portions of the several beams 19 being curved downwardly to heavy counterbalancing members 24 to which the beams are connected, such counterbalancing members 24 being preferably in the form of massive blocks of reinforced concrete. The beams 19 are also positively connected to the members 22 and 23 so as to be held against upward movement with respect thereto as well as against downward movement. The beams 19 are of any approved form comprising in the construction shown top and bottom structural forms 25 and 26, and diagonally arranged brace bars 27 and 28. The arrangement is such that the forward portion of the canopy is supported with the required margin of safety, and is braced with the required firmness with respect to the lifting effect of the wind underneath the canopy.

In the arrangement shown, the canopy portion 16 comprises opaque closure means by which shade is provided as well as protection from rain and the like. The canopy portion 17 on the other

hand comprises closure means in the form of glass or other suitable material of a type adapted to permit the passage of the ultraviolet and the infra-red portions of the sunlight therethrough, 5 with the resultant beneficial effects by which the value of the sunshine may be enjoyed by the people underneath the canopy portion 17 without subjection to the cold or other objectionable features of the weather. Such closure means permitting the passage of the actinic rays there- 10 through is of any approved form and is mounted in any approved manner.

Referring now to Fig. 3, which shows the building 18 and its related parts, 29 indicates a pit 15 preferably lined with concrete, in which I have provided a pedestal 30 adapted to support the building 18, the building being provided with downwardly projecting bars 31 at opposite sides which act as guides for the building as it is moved 20 up and down with respect to the pit, the lower ends of the bars 31 being braced by diagonal bars 32. The building 18 is counterbalanced by means of weights 33 connected to the building by means of cables 34 extending over pulleys 35 25 revolvably mounted in position in the pit 29 near the upper end thereof. The means for moving the building 18 up and down with respect to the pit comprises cables 36 passing over suitable pulleys at the upper end of the pit, passing thence 30 downwardly about pulleys 37 near the bottom of the pit, and thence inwardly into operative engagement with a capstan or sheave 38 which is driven by an electric motor 39. The roof 40 of the building in the construction shown is flat and 35 is of a size to fill the opening at the upper end of the pit. The arrangement is such that the roof 40 is level with the surrounding ground about the pit when the building is in its lowermost position.

With the building 18 in its raised position as is 40 shown in Fig. 1, such building is available for use by the timers and other track officials. When it is time for a race, the building 18 can be quickly lowered to the position shown in solid lines in Fig. 3, so as to leave a clear view of the opposite 45 side of the track from any and all points of the grand stand.

While I prefer to employ the form and arrangement as shown in my drawings, it is to be understood that my invention is not limited thereto, except so far as the claims may be so limited 50 by the prior art, it being understood that changes might well be made in the particular arrangement employed without departing from the spirit of my invention.

I claim:—

1. In a race track plant, the combination of a 5 grand stand, promenade grounds behind the grand stand, a unitary roof structure comprising a plurality of beams arranged side by side across the grand stand and extending to the rear of said promenade grounds behind the grand stand, means at the rear portion of the grand stand for supporting said beams at intermediate points therealong in substantially balanced condition, 10 enclosure means between said beams covering at least the greater portion of both the grand stand and the promenade grounds, and anchoring devices connected with said beams at the rear edge portion of the promenade grounds adapted in 15 combination with said beam supporting means to hold the beams in their operative elevated positions.

2. In a race track plant, the combination of a 20 grand stand, promenade grounds behind the grand stand, and a unitary roof structure over both the grand stand and the promenade grounds comprising a series of long heavy beams side by side supported at intermediate points therealong at the rear portion of the grand stand 25 with their front end portions in substantially horizontal elevated position above the grand stand and their rear end portions curved downwardly opposite the supporting means, means for anchoring the rear end portions of said beams 30 down in rear of the promenade grounds, and enclosure means between said beams covering at least the greater portion of both said grand stand and said promenade grounds.

3. In a race track plant, the combination of a 35 grand stand, promenade grounds behind the grand stand, a unitary roof structure comprising enclosure means over both the grand stand and the promenade grounds, and a series of long 40 heavy beams arranged side by side supporting said enclosure means with their front end portions in elevated position over the grand stand and their rear end portions curved downwardly over and behind the promenade grounds, supporting means at the rear portion of the grand 45 stand engaging approximately the middle portions of said beams, and anchoring means connected with the rear end portions of said beams at the rear portion of said promenade grounds adapted by themselves in cooperation with said 50 supporting means to hold said roof structure in operative elevated position.

WILLIAM E. GOLDEN.
